UNITED STATES PATENT OFFICE.

HENRY POAGE, OF MILL POINT, WEST VIRGINIA.

CHURN-OPERATING DEVICE.

1,382,316.

Specification of Letters Patent. Patented June 21, 1921.

Application filed July 2, 1920. Serial No. 393,532.

To all whom it may concern:

Be it known that I, HENRY POAGE, a citizen of the United States, residing at Mill Point, in the county of Pocahontas and State 5 of West Virginia, have invented certain new and useful Improvements in Churn-Operating Devices, of which the following is a specification.

This invention relates to churn operating 10 devices, adapted particularly for use in connection with barrel churns, and has for its primary object to provide mechanism of simple construction for greatly simplifying the churning operation and minimizing the 15 amount of effort required for the operation of such devices.

A further object of the invention is to provide a machine of such character that barrel churns of the type now generally known 20 and in use may be quickly and easily applied to the machine to be operated thereby, and which require no changing or modification of parts to enable them to be operatively held and operated by the machine.

25 A further object is the provision of means on a machine of the character described whereby churns varying in size may be applied to and operated by the dasher operating mechanism.

30 A further object is to provide a machine of the character stated which has its parts so arranged and located upon the supporting frame, and which accommodates the churn in such manner that the device is 35 evenly balanced, whereby danger of the machine being overturned is obviated, and whereby the weight, and strains due to the operation of the machine are evenly distributed to all parts of the supporting structure.

40 A still further object of the invention is the provision of a machine of the character and for the purposes stated which is featured by means of an improved nature for 45 detachably holding the dasher rod to the operating arm of the mechanism.

With these objects in view, together with others which will appear as the description proceeds, the invention consists in the novel 50 construction, combination and arrangement of parts, all as will be described more fully hereinafter, illustrated in the drawings, and particularly pointed out in the claim.

In the drawings:

55 Figure 1, is a side elevation of a churn operating machine constructed in accord-

ance with my invention, the machine being shown with a conventional form of barrel churn applied thereto,

Fig. 2, is an end view of the improved 60 machine, and

Fig. 3, is a top plan view of the machine.

Generally stated, the invention consists in

a supporting structure constituting a frame

of light construction which can be moved 65

about easily and without much effort, and

upon the lower part of which a suitable rest

or platform is arranged for the reception of

the churn. The operating mechanism is

arranged upon the frame at the upper part 70

thereof, and consists mainly of a rock arm

to be attached to the upper end of the churn

dasher rod, a support for the rock arm,

means in connection with said arm and sup-

port whereby the arm may be made adapt-

able to churns of various sizes, a crank,

means for manually operating the crank

with a minimum amount of exertion, and a

connection between the crank and the rock

arm. Furthermore, the rock arm overlies 80

the churn holding platform in such manner

that the dasher rod and arm are properly

centered, whereby the connecting operation

is facilitated, regardless of the size or type

of churn applied to the machine. The at-

tachment of the dasher rod to the rock arm

is accomplished by means of a spring pressed

pin; the latter being secured to the arm so

as to prevent loss of the same, and this

spring at all times exerts pressure upon the

pin so as to hold the latter securely in place.

More particularly, the frame comprises

uprights indicated at 4, arranged apart in

proper spaced relation, connected together

at their upper ends by longitudinal bars 5

95 and transverse bars or beams 6. The end

posts or uprights are connected near their

lower ends by the transverse bars 7; the lat-

ter constituting supports for the platform 8

upon one end of which the churn 9 rests.

100 The platform may be provided with blocks

or cleats 10 to hold the churn in proper po-

sition on the platform, and one of these

cleats (or both) may be made adjustable so

that churn barrels of various sizes may 105

be accommodated. To this end, the outer

cleat, indicated at 11, is provided with

spaced apertures for the reception of bolts

12, the bolts extending downwardly through

the slots 13 arranged in spaced parallel re-

lation in the platform. This construction

permits of the cleat 11 being adjusted longi-

tudinally of the platform and engaging the lower end of the churn, as will be understood. It will be noted, furthermore, that the churn is disposed midway of the longitudinal edges of the platform, and the cleats 5 maintain the churn in such position.

An upright or post 14 is arranged at the upper end or on top of the frame, and substantially midway the ends thereof. This 10 upright, in the present instance, comprises a pair of metallic strips secured at their lower ends to the longitudinal bars of the frame and meeting over the longitudinal center of the frame. The upper ends of the strips are 15 spaced slightly apart and receive between them the rock arm 15. The said upper ends of the strips have alined openings to receive the pivot pin or bolt 16; the said bolt passing through one of the spaced openings 17 in the 20 rock arm 15. This particular construction permits of the rock arm being bodily adjustable longitudinally of the frame, whereby to be adaptable to churns varying in size, and whereby the throw of the rock arm may be 25 varied.

The frame has arranged transversely thereof and near one end, a crank shaft 18. This shaft is arranged in suitable bearings as shown, and has its crank 19 disposed above 30 the longitudinal center of the platform 8. This crank is connected, as by means of the link 20, with the adjacent end of the rock arm 15, and it will be obvious that rotation of the crank shaft will cause the said arm to 35 rock. A jack or power shaft 21 is also journaled upon the upper end of the frame in suitable bearings, and has secured thereto a gear 22, in mesh with the pinion 23 on the crank shaft 18. The power shaft, in the 40 present instance, receives its rotation by operation of the crank or handle 24, but it will be understood that if desired this handle may be replaced with a belt wheel or pulley so that the device may be coupled up with a 45 source of mechanical power. The crank shaft has secured to its outer end a balance or fly wheel 25, whereby the motion of the crank shaft will be steadied and the rotation made uniform.

50 The outer end of the rock arm 15 is provided with means for the attachment of the same to the dasher rod 26 of the churn. The outer end of the arm is provided with an opening to receive the pin 27, the latter also 55 passing through an opening in the upper end of the dasher rod. In the present instance, the end of the rock arm is forked or bifurcated, thus providing spaced arm portions to receive between them the end of the dasher rod. The pin 27 is attached to the outer end 60 of a flat spring 28, riveted or in any other preferred manner secured to the side of the rock arm inwardly from the outer end of the latter. This particular construction permits

of the pin being easily and quickly applied to 65 or removed from the dasher rod, and the pin cannot become lost or misplaced.

The upper end of the dasher rod may be provided with a metallic plate 29, pivoted thereto as at 30, and the upper end of which 70 is received between the furcations at the end of the rock arm. This arrangement, constituting a link construction, obviates wear on the dasher rod and compensates for any inaccuracy in adjustment of the churn on the 75 platform 8.

It will be noted that the power machinery and rock arm are so arranged on the frame that the weight thereof is equally distributed to the supports of the frame, and that 80 the combined weights of the churn and the machinery evenly balance the device so that the danger of overturning of the machine is overcome. Furthermore, the manner in which the mechanism is disposed upon 85 the frame assures even motion during operation of the machinery.

From the foregoing, it is obvious that I 90 have provided a machine for operating barrel churns which is of extremely simple construction, inexpensive to manufacture, and which has its parts so constructed and assembled as to minimize the opportunity for wear, disorder or breakage. The machinery is so geared that it will be very easy to 95 operate, and the simplicity of the manner of connecting the rock arm to the dasher rod enables churns to be applied to or removed from the machine without the necessity of special skill or tools.

100 While the above is a description of the preferred embodiment of the invention, it will be understood that various changes in the minor details may be made without departing from the spirit of the invention as 105 defined by the claim.

I claim:—

110 In a churn operating device, a frame including spaced parallel top rails horizontally disposed, an inner rail between said top rails in the same plane and parallel with the latter, the said inner rail being closer to one of said top rails than the other, a gear shaft supported between said inner rail and the adjacent top rail, a gear on said shaft 115 lying between said inner and adjacent top rails, a crank shaft supported by the said inner rail and the remote side rail, a pinion on said crank shaft in the space between said inner rail and its adjacent top rail and in mesh with the said gear, a rock arm supported by said frame, a link connecting said crank shaft with one end of said rock arm, and means for connecting the other end of 120 said rock arm with a churn dasher.

125 In testimony whereof I affix my signature.

HENRY POAGE.
